UNITED STATES PATENT OFFICE.

FREDERICK MEYER AND ROBERT L. COMMONS, OF CHICAGO, ILLINOIS,
ASSIGNORS OF ONE-THIRD TO KOLBEN JOHNSON, OF SAME PLACE.

WIRE-COILING MACHINE.

SPECIFICATION forming part of Letters Patent No. 550,991, dated December 10, 1895.

Application filed March 18, 1893. Renewed May 11, 1895. Serial No. 548,992. (No model.)

To all whom it may concern:

Be it known that we, FREDERICK MEYER and ROBERT L. COMMONS, of Chicago, in the county of Cook and State of Illinois, have invented certain new and useful Improvements in Wire-Coiling Machines; and we do hereby declare that the following is a full, clear, and exact description thereof, reference being had to the accompanying drawings, and to the letters of reference marked thereon, which form a part of this specification.

This invention has for its object to provide improvements in wire-coiling machines, one of which improvements is the adaptation of a single machine to the production of coils of various forms, sizes, and pitch, including open conical coils or double conical coils, such as are used for bed-springs.

The nature of the improvements will be understood from the accompanying drawings, which illustrate our invention in a practical form, together with certain modifications in some of the elements thereof.

Figure 1 in said drawings is a side elevation of a complete machine. Fig. 2 is a plan view of the machine shown in Fig. 1. Fig. 3 is an end view of the machine of Fig. 1. Fig. 4 is an end view corresponding with that shown in Fig. 3 with the parts concerned in severing the coils omitted. Fig. 5 is a vertical section in the line 5 5 of Fig. 4. Fig. 6 is a side elevation of portions of the machine, showing a coil-cutter of different construction from that shown in Figs. 1, 2, and 3, and also a somewhat different construction of the wire guiding and bending devices. Fig. 7 is a plan view of the modified constructions shown in Fig. 6. Fig. 8 is a front elevation of the coil-forming devices shown in Figs. 6 and 7. Fig. 9 is a front view of the cutters shown in Figs. 6 and 7. Fig. 10 is an enlarged front view of further modifications in the coil-forming devices. Fig. 11 is a plan section of the construction shown in Fig. 10, taken on line 11 11 of said figure. Fig. 12 is a vertical section in the line 12 12 of Fig. 10, the wire-feeding heads and parts of the shafts carrying them being shown in side elevation. Figs. 13 and 14 are respectively front and side views of an attachment de-

sirably employed in making open springs, either cylindric or conical.

A represents the machine-bed, having secured thereto uprights A', A², and A³.

B is a shaft mounted in bearings a a' in the uprights A² A³ and projecting through an opening in the upright A', beyond which it is provided with a head or extremity B', having a circumferential groove b. Said shaft B is also supported in the upright A' by resting in a surface bearing in a cross-bar a². (Represented in dotted lines in Fig. 4 and other figures and seen in section in Figs. 5 and 12.) The shaft B extends beyond the bearing a', where it is provided with a driving-pulley, and between the bearings a and a' it is further provided with a worm b' and a pinion b².

B² is a second shaft arranged above the shaft B and desirably at an inclination thereto, as shown in Figs. 1 and 5, and having its principal bearing at a³ in the upright A³, as seen in Figs. 1 and 2. Said shaft B² extends forwardly over the end of the shaft B, where it also has a head B', provided with a circumferential groove b, which coincides with the corresponding groove in the shaft B, the surfaces of the two shafts or of their heads B' proximating each other and the coincident grooves therein forming a passage-way between them for the wire to be coiled. The free end of the shaft B² is pressed down and held to its work by a movable superposed bearing-block a⁴, mounted to slide vertically in the slotted upright A', and adjustable vertically by the adjusting-screw a⁵. The shaft B² projects back of its bearing a³, where it is provided with a pinion b³, that meshes with the pinion b² on the shaft B.

At each side of the grooved ends or heads B' B' of the shafts B B² are placed wire-guides, serving, also, as wire-benders, so that a wire fed over them, by being clamped between the rotating heads B' B', will be bent upwardly and so coiled.

C is the wire-guide on the entering side of the feeding-heads B', and C' the guide and bender on the opposite side of said heads. As here illustrated, these guides are vertically movable, so as to adapt them to produce coils

of different diameters, or, if moved while the coil is being made, to produce a coil of differing diameter in its different parts. The wire guide and bender C' on the emerging 5 side of the wire-feeding heads is also shown to be adjustable toward and from the coiling-shafts, and in some figures of the drawings it is also shown as vertically adjustable with reference to the opposite guide. Both said 10 guides are shown in all figures of the drawings containing them as being mounted on a single movable support C². This support C² is preferably an arm pivoted at one of its ends upon a pivot c, attached to the machine-frame, 15 and beneath its opposite or free end is arranged a suitable adjusting device. Such adjusting device, as shown in Fig. 10, consists of a simple screw c', threaded vertically into the bed of the machine, and therefore adapted 20 to hold the pivoted arm C² fixedly at any desired elevation.

In Figs. 1, 2, 4, 5, and 6 the adjusting device is shown as the end of a centrally-pivoted lever D. This lever, having its fulcrum at 25 d, projects rearwardly toward a point opposite the worm b', where its rear arm d' is engaged by a cam E, secured upon a shaft E', which has a pinion e engaged with said worm. The rotation of the cam-shaft E' therefore 30 results in the slow raising and depressing of the wire-guides C C' in the operation of forming a coil, with the obvious effect of making the coil of different diameters in its different parts.

35 Describing the wire guides or benders more particularly, the guide C is shown as an upwardly and laterally extended arm having a groove c² in its upper surface, through which groove the wire to be coiled passes to the 40 feeding-heads B' B' from an overhead reel. As shown in Figs. 1, 2, 3, and 4, said wire guide and bender C is rigidly secured to the vibratory arm C², but as shown in Figs. 6, 7, 8, 10, and 11 it is pivoted to said vibratory arm on a pivot c³, transverse to the arm. When so pivoted, it is adapted to be retracted to facilitate the insertion of the end of a wire between the coiling-heads, and after such insertion of the wire it will be lifted to 50 its working position and secured in any suitable manner. The means for so securing it consists, as shown in the drawings, of a latch c', provided with a hook at its end, which engages a suitable surface on the arm C², as indicated by dotted lines at c⁵ in Figs. 8 and 10. The latch is or may be made to automatically 55 engage by means of a spring c⁶, placed under the upper arm of the latch, as shown most clearly in Fig. 8.

60 The wire-bender C' is a block having a groove c' upon its upper surface arranged opposite the grooves of the feeding-heads B' B, the said groove c' being in line with that of the opposite guide C or inclined thereto, as 65 may be desired or as called for by the pitch or closeness of the coil to be formed. Different blocks C', having the r grooves at differ-

ent inclinations, may be provided, so that by the substitution of one block for another more or less open or close coils may be formed 70 thereby. The block C' is desirably adjustable toward and from the feeding-heads B', and it is so shown in Figs. 2, 3, and 4, wherein it is held to the arm C² by screws c⁸, (either vertical, as shown in Figs. 3 and 4, or horizontal, as shown in Figs. 10 and 11,) an adjusting-screw c⁹ being provided to bear against the block to move and hold it when the holding-screws are loosened. In Fig. 10 the block C' is both horizontally and vertically adjustable with respect to the arm C², being connected with the said bar through the medium of an arm C³, which is pivoted at c and is supported by an adjusting-screw C⁴, that rises beneath its free end through the bar 85 C². In Fig. 8 said block C' has only a vertical adjustment, being rigidly attached to the pivoted arm C³, of which it forms or may form an integral part, and is supported by the adjusting-screw C⁴, as in Fig. 10. If 90 the bottom surface of the groove c' in said block be curved downwardly at the end of the block which proximates the feeding-heads, this single vertical adjustment of said block, as shown in Fig. 8, will measurably take the 95 place of the horizontal adjustment provided for in other figures or of the horizontal and vertical adjustments shown in some of said figures.

The device for cutting off the coils at given 100 intervals in the operation of the machine may be variously constructed. As shown in Figs. 1 and 2, it consists of a pair of cutters F F', the former of which is fixed in front of the coiling devices and the latter of which is 105 mounted on the end of a vibrating lever F². This lever is connected with a bell-crank G by a preferably extensible rod F³, pivoted at its ends to the lever and bell-crank. Periodic motion is given to the bell-crank G and 110 through it to the cutters by means of a projection H, (in the nature of an arm,) mounted on the shaft E', which projection rises beneath the arm g of the bell-crank and tilts the same forwardly, finally passing it and allowing it to retract. The retraction of the 115 parts moved by this projection H is effected, in the construction shown in Figs. 1 and 2, by a spring H'.

In the construction of the cutting mechanism shown in Figs. 6 and 7 the movable cutter F' is mounted on an arm f of a rock-shaft F², to which is secured a lever G', that extends backward into engagement with the projection H on the shaft E'. The rock-shaft, 120 with its knife-carrying arm f and its lever G', answers, essentially, to the bell-crank G of Figs. 1 and 2, but extended and arranged to directly carry the movable knife instead of operating it through intermediate devices. 125 The retracting-spring H' in this modified construction is seen plainly in Fig. 6, and h, in both Figs. 1 and 6, is an adjustable stop limiting the retractive movement of the cutter F'.

In the operation of the machine above described the wire-feeding heads B' B' by pressing firmly upon the wire embraced between them in their coincident grooves draw the 5 same forward over the guide C and push it forward over the guide and bender C', the elevation of these guides and benders, and especially of the bender C', obviously determining the degree of bend given to the wire in 10 forming the coil, and consequently the diameter of the coil. At the same time the lateral inclination of the groove c⁷ in the bender-block C' determines the pitch of the coils. When 15 the supporting-arm C² of the benders is stationary, the spring or series of coils formed will be of uniform diameter, as indicated in Figs. 10, 11, and 12, while if the said supporting-arm C² be raised and lowered during 20 the operation of forming a series of coils the diameter of the spring produced will vary in different parts of its length, as shown in Figs. 1 and 2. Hence the machine is adapted to form either coils of uniform diameter or a series of 25 reversed cones. The dotted lines in Figs. 1 and 2 show one half of a double-reversed conical bed-spring, the benders being in said figures at their highest elevation and the individual coil, which is at this moment being 30 made, being the smallest in the spring. In the advance of the machine said benders will be lowered and the coils will be gradually increased in diameter, as they have been just 35 previously diminished, thus forming two cones with their apices joined. In the absence of cutting-off devices there will be formed a series of reversed cones joined alternately at 40 their bases and apices. The cutters are shown to be so arranged in position and to be so timed as to sever the wire in the largest coils and 45 therefore to form the familiar bed-spring indicated and known as the "double-cone" spring, in which the ends are larger than the middle. These cutters may, of course, be otherwise timed to make either a shorter spring or a longer one, or to make cylindric springs of 50 any desired length. Said cutters may also be entirely disused, if desired, and a continuous coil of any length and degree of closeness or openness produced.

50 The device shown in Figs. 13 and 14 consists of a transversely-arranged plate I, supported, preferably, on the bender-supporting arm C², and in its most effective form provided with a winding front face I', outside or 55 in front of which the wire of an open coil passes after leaving the bender C'. It serves to give a spreading or forwardly bending action upon the coiled wire, giving the coils a more uniform pitch and correcting the irregularities in this particular which are apt to arise in its absence from unequal density in different parts of the wire.

As a means of varying the range of vertical movement of the benders, the lever D is shown as having its fulcrum d movable with 60 respect to the benders and the actuating-cam E, said fulcrum-pivot being supported on a

base-piece d², which may be set and secured upon the main bed of the machine at a greater or less distance from the actuating cam-shaft 70 E' by means of the holding-screws d³, passing through slots d⁴ in the said base-piece d².

The grooved heads B' B', applied to the converging ends of the shafts B², though shown as conical, may obviously be of other 75 form—as, for example, by narrowing their circumferential surfaces or reducing their diameter at the opposite sides of the grooves, when their effective surfaces with reference to the wire will still remain the same. The 80 conical form is preferable, as giving mutual support in the absence of a wire. Said heads may also be made integral with the shafts or detachable and changeable. The latter construction (indicated in Fig. 12) is preferable 85 for obvious reasons.

We wish it to be understood that the following several claims apply to those features of our invention which are specified therein and are adapted to be used without others 90 not therein expressed, and that the omission of parts not necessary to a given operation does not constitute a departure from the invention.

We also wish it to be understood that various 95 modifications and changes may be made in the construction of the machine without departure from the invention.

We claim as our invention—

1. In a wire-coiling machine, the combination, with rotary wire feeding devices, of a vertically movable bender support C² and a wire bender C' adjustably secured to said support, substantially as described.

2. In a wire coiling machine, the combination, with rotary wire feeding devices, of a vertically movable bender support C², means for automatically giving to the latter rising and falling movements during the operation of coiling, and a wire bender C' adjustably secured to said support, substantially as described.

3. In a wire coiling machine, the combination, with rotary wire feeders, of a vertically movable bender support C², and an obliquely 115 grooved bender block C' adjustably connected with the support, substantially as described.

4. In a wire coiling machine, the combination, with wire feeding devices, of a vertically movable support, automatic means for giving 120 vertical movement to said support during the operation of coiling, a wire guide connected with said support for directing the wire to the feeding devices, and a wire bender C' adjustably connected with said support, substantially 125 as described.

5. In combination with a wire feeding device and a vertically movable bender support, two wire benders arranged one on each side of the feeders and connected with said support.

6. In combination with the wire feeders and the vertically movable wire bender support C², the wire guide C pivoted to the bender

support and provided with a latch device for holding it in working position.

7. The combination, with wire feeding devices, of a vertically movable bender support, 5 a wire bender arranged upon said support at the side of the feeders from which the wire emerges, means for adjusting said bender upon the support both vertically and horizontally in the plane of the wire, and mechanism 10 for raising the bender support during the operation of making a coil.

8. In combination with the rotating shaft B provided with a pinion and a worm, a relatively inclined shaft B² also provided with a 15 pinion meshing with that upon the shaft B, the said shaft B² forming with the shaft B a wire-feeding device, a vertically movable arm or bar C², benders mounted upon said arm on opposite sides of the wire-feeding portions of 20 the shafts B B², a lever D arranged beneath the bender support C², and a transverse shaft E' provided with a spur engaged with the worm on the shaft B and also provided with a cam engaging the lever D, substantially as 25 described.

9. The combination, with a worm shaft B and a relatively inclined shaft B² geared therewith and forming a wire feeder, substantially as described, of the bender support C² carrying benders on opposite sides of the wire-feed- 30

ing portions of said shafts, a cam shaft E' rotated by the worm and provided with a cam E and with a projection H, a lever D engaged with the bender support and with the cam E, and cutters actuated by the projection H. 35

10. In combination with a wire feeder and a vertically movable bender support and a cam E, the centrally pivoted lever D adapted to have sliding engagement with both the bender support and the cam, and a movable 40 part carrying the central fulcrum pin of said lever, substantially as described.

11. In combination with a wire-feeding device and a wire-bending device together arranged and adapted to produce conical coils, 45 a spreader consisting of a plate arranged immediately in front of and adjacent to the said coil-forming devices and provided with a broad oblique or winding face arranged to bear against the emerging coil in a direction 50 generally parallel with its axis, substantially as described.

In testimony that we claim the foregoing as our invention we affix our signatures in presence of two witnesses.

FREDERICK MEYER.
